UNITED STATES PATENT OFFICE.

EDWARD A. BIGLER, OF AUBURN, ILLINOIS.

AUTOMATIC LATCH MECHANISM FOR GATES.

Application filed October 6, 1924. Serial No. 741,999.

The invention relates to latches such as are used in conjunction with automatic farm gates and similar structures.

The purposes of the invention are to provide latch mechanism either double or single, of simple and sturdy construction, able to withstand severe use and protected against such accumulation of snow and ice as might interfere with the operation of the mechanism; to provide latch mechanism which will not be rendered ineffective by the sagging of the gates with which it is used; to provide latch mechanism which may be constructed at relatively small cost, and applied on gates already in use; and to provide improved structural details as will hereinafter appear.

With these ends in view the invention consists in the new and useful features of construction and combinations of parts shown in the accompanying drawings and now to be described and finally recited in the claims.

Figure 1 is a front elevation of a double latch mechanism of preferred construction embodying my invention; Fig. 2 is a right-hand side elevation of the same mechanism; Fig. 3 is a horizontal transverse section taken on the line 3—3 of Fig. 1; Fig. 4 is an enlarged perspective view of the right-hand angular block as seen from below, looking upward; showing two aprons integral with the block and showing the spiral runway and the adjacent lug integral with the base plate; Fig. 5 is a diagrammatic perspective view of a double latch mechanism of modified construction, including weighted annular blocks oscillative on inclined axes; and

Fig. 6 is a diagrammatic perspective view, on a reduced scale, showing latch-mechanism of modified construction embodying a single annular block operative in one direction by a latch blade carried by the gate frame upon closing the gate, and operative by hand in the same direction to permit opening of the gate.

The same reference numerals designate the same parts in all the views.

The present invention is primarily designed for use in conjunction with what are known as gravitating gates—that is to say, gates swinging on a shiftable axis, the construction being such that when one side of

the gate frame will rise, carrying the latch blade above the latch blocks and will swing outwardly to open position and when the same end of the axis of the gate is shifted in the opposite direction the gate frame will swing inwardly to closed position. The latch blade is usually connected with and extends outwardly, lengthwise of the gate frame to engage and co-operate with the latch mechanism now to be described.

The latch blade which is not part of the present invention—may be of any usual construction; it is therefore unnecessary to show and describe the latch blade in detail.

The preferred latch mechanism shown in the drawings and now to be described is a "two-way" mechanism, operative from either direction, going or coming, but it is obvious that the right-hand oscillative angular block may be utilized to co-operate with a gate frame which swings to the left to close the gate and swings to the right to open the gate, and similarly the left-hand oscillative angular block may be utilized to co-operate with a gate frame which swings to the right to close the gate; and swings to the left to open the gate; in either case the oscillative block will be operated by hand to permit opening of the gate.

The preferred automatic-latch-mechanism (Figs. 1, 2, 3 and 4) comprises a base-plate 7 having at its lower end outwardly extending integral lugs 9 and 20; and an outwardly extending integral flange 8 near its upper end. The base-plate is secured on the gate post 6 by bolts 18, or other suitable means. Vertical blocks 10 and 12 of angular cross section are supported on the base-plate parallel to each other. Aligned bosses 13 on the back of the block 10 have lengthwise, bores 14 to receive a rod 17 which extends through the flange 8, the bosses 13 and the lug 9 to connect the block 10 with the base-plate so that the block will oscillate freely and slide on the rod.

Similarly, the block 12, of angular cross section, has on its back aligned bosses 15 to receive a rod 19 extending through the flange 8, the bosses 15 and the lug 20 to connect the block with the boss so that the block will oscillate and slide on the rod.

The block 10 has a downwardly extending integral front-member 21 and a downwardly extending integral side member 30. For convenience in description I call the part 21

(Figs. 3 and 4) the front apron and the part 30 the side apron. The aprons 21 and 30 protect the run-way 23 from dirt, snow and ice.

5 The block 12 has similar downwardly extending aprons 22 and 31 which protect the run-way 24; spiral inclined runways 23 and 24 are preferably integral with the base-plate adjacent to the lower ends of the respective blocks 10 and 12. Yokes 25 and 26 near the lower ends of the respective blocks 10 and 12 are preferably integral with the blocks and carry wheels 27 and 28 which roll on the respective run-ways.

10 Cotter pins 29 extend through the lower terminals of the rods 17 and 19 and prevent accidental displacement of the rods.

In use the block 10 will be operated by the usual latch-blade or pin on the gate 20 frame, moving in the direction indicated by the arrow X to admit the latch-blade into the space between the latch-blocks, and the block 12 will be operated by the latch-blade on the gate-frame, moving in the direction indicated by the arrow Y, to permit the latch-blade to take position between the blocks.

A quarter-rotation of the block 10 in the direction X causes the wheel 27 to run upward on the runway 23 (Fig. 4) to raise the block and when the latch-blade passes the outwardly extending member of the block, the block will gravitate downwardly and will cause the wheel 27 to run downward on the runway to restore the block to its original position, so that one lengthwise member of the block engaging on the face of the plate 7, will prevent reverse rotation of the block, and the block will prevent reverse movement of the latch-blade; and similarly a quarter-rotation of the block 12 in the direction Y causes the wheel 28 to run upwards on the runway 24 to raise the block and when the latch-blade passes the outwardly extending member of the block, the block will gravitate downwardly to cause the wheel to run downwardly on the runway to automatically return the block to its original position.

50 From the foregoing it is obvious that the latch-blade carried by the gate frame swinging in either direction may effect a quarter rotation of the proper block to cause the blade to enter the space between the blocks 10 and 12, but the blocks gravitating downward as described will cause the wheels 27 and 28 to run downward on the runways 23 and 24 to effect reverse rotation of the blocks back to their original position and the blocks 60 will prevent lateral withdrawal of the blade in either direction.

The latch-blade can however, be withdrawn by lifting the blade out of the space between the latch-blocks; or by sliding the 65 blade horizontally outward.

The "one-way" latch mechanism shown in Fig. 6 comprises a base plate 32 secured on the post 33; one angular block 34, in the present instance a right hand block, a vertical shaft 35 on which the block 34 slides and oscillates, a runway 36, similar to the runway 23, a roller 38 traveling on the runway 36 and a vertical stationary stop 37 limiting inward movement of the latch (not shown) carried by the gate frame and acting on the block 34, upon closing the gate to rotate the block in the direction indicated by the arrow Z to permit the blade to pass the block 34, whereupon the block 34 will gravitate and rotate back to its original position, as has already been set forth in the description of the operation of the block 10. To release the latch-blade the block 34 will be rotated by hand in the direction indicated by the arrow Z to permit the outwardly moving latch-blade to pass the block 34.

The two-way latch mechanism of modified construction shown in Fig. 5 comprises among other things a base plate 40 secured on the post 42 by bolts 41. The post has chamfered parts 43. The base plate has inclined buffer members 44 conformed to the parts 43.

Angular blocks 45 and 46 preferably of cast iron, have integral weights 51 and 52, which cause the blocks to gravitate in a manner to be described later. The blocks 45 and 46 are supported on the respective bosses 49 and 50 which are integral with the base plate. Inclined rods 47 and 48 extend through the forwardly extending flange 53 of the base plate and lengthwise through the respective blocks 45 and 46 and rest in the respective bosses 49 and 50.

The operation of the mechanism shown in Fig. 5 is as follows: If the gate frame swings in the direction indicated by the arrow V, to close the gate, the latch blade carried by the gate frame will strike the member 54 and thereby rotate the block 45 sufficiently to permit the blade to pass the block and thereupon the weight 51 acting by gravity, will rotate the block back to its original position in contact with the buffer 44 which will stop the block. If the gate frame moves in the direction indicated by the arrow W, to close the gate, the latch blade carried by the gate frame will strike the member 55 to rotate the block 46 to admit the latch blade to the space between the blocks and thereupon the weight 52 will act by gravity to rotate the block back to its original position against the buffer 44. In either case, the proper block will be operated by hand to permit the withdrawal of the latch blade from the space between the angular blocks 45 and 46.

Having fully described my invention, what I claim as new and desire to secure by Letters Patent is:

1. Latch mechanism comprising a station-

ary base plate; a pair of oppositely acting oscillative latch blocks of approximately rectangular cross section, each adapted to gravitate downwardly and outwardly and each having integral downwardly extending curtain members; and latch-block operating means protected from snow and ice by the curtain members of said latch-blocks.

2. Latch mechanism comprising a stationary base plate having an outwardly extending flange having two holes spaced suitably apart from each other to receive hinge-bolts in the respective holes, also having two inclined runways spaced apart from each other according to the spacing of the holes in said flange, and two outwardly projecting lugs having holes in line with the respective holes in the flange of the base plate; and a pair of sturdy latch-blocks of approximately rectangular cross section, each adapted to be operated in one direction by a latch blade carried by an inwardly swinging gate and each having at the juncture of its sides hinge-members having aligned holes adapted to receive a hinge-bolt; each of said blocks having also integral downwardly extending curtain-members; rotative wheels on said respective latch blocks between said apron members and adapted to travel on said respective runways, protected from snow and ice by said curtain-members; and hinge-bolts extending through the respective holes in the flange of said base plate, through said lugs on the base plate and through the hinge-members of the latch-blocks, to permit either latch-block to turn inwardly upon engagement by a latch blade carried by a gate swinging inwardly either right or left to admit the blade into the space between the latch-blocks, and to permit the latch blocks to gravitate downwardly and stop against the base plate to prevent opening the gate in either direction.

3. Latch mechanism comprising a stationary base plate having upper and lower outwardly extending members each having a hole in line with a corresponding hole in the other; a hinge-bolt extending through the holes in said outwardly extending members; and a latch-block of angular cross-section slidable on said hinge-bolt and having flat sides at an approximate right angle relative to each other; said angular latch block being free to oscillate on said bolt within an arc limited by the striking of the respective flat

sides of said latch-block against the outer face of said base plate.

4. Latch mechanism comprising an upright base plate having upper and lower outwardly extending members; a hinge-bolt 60 extending through said outwardly extending members; a latch block of angular cross section oscillative and slidable on said hinge-bolt and having flat sides at an approximate right angle relative to each other and having also integral curtain members, one a continuation downwardly of one flat side of the latch block and the other a diagonal downwardly extending member integral with the same latch block; and block 65 operating means protected from ice and snow by said curtain members and adapted to slide said latch block upwardly and permit it to gravitate downwardly on said bolt during the oscillations of the locking block. 70

5. A latch unit comprising a stationary base plate having an outwardly extending flange with a hole to receive a hinge bolt, having also an inclined runway and an outwardly extending lug having a hole in line 80 with said hole in said flange; and a sturdy latch block of approximately angular cross section having at the juncture of its side members lugs which have aligned holes adapted to receive a hinge bolt, said block 85 having also integral downwardly extending curtain members; a rotative wheel carried by said latch block between said curtain members and adapted to travel on said inclined runway, protected from snow and ice 90 by said curtain members; and a hinge bolt extending through the flange and the lug on said base plate and through the hinge members of said latch block; said latch block slidable upwardly on said hinge bolt during 95 upward travel of said wheel on said runway and gravitating downwardly and stopping against said base plate.

6. Latch mechanism comprising a stationary base plate, an elongated latch block having side members in angular relation to each other, a bolt connecting said latch block pivotally and slidably relative to said base; said block free to oscillate right and left and free to slide on said hinge bolt and stop 100 against said base plate. 105

In witness whereof, I have hereunto signed my name at Springfield, Illinois, this 13th day of June, 1924.

EDWARD A. BIGLER.

Certificate of Correction.

Patent No. 1,642,534.

Granted September 13, 1927, to
EDWARD A. BIGLER.

It is hereby certified that error appears in the printed specification of the above-numbered patent requiring correction as follows: Page 1, line 43, for the word "annular" read *angular*; same page, line 66, for "port" read *part*; and that the said Letters Patent should be read with these corrections therein that the same may conform to the record of the case in the Patent Office.

Signed and sealed this 18th day of October, A. D. 1927.

[SEAL.]

M. J. MOORE,
Acting Commissioner of Patents.
